DESIGN FOR A HANDLE FOR A SAFETY RAZOR

John B. Buller, St. Joseph, Mo.

Application December 14, 1942, Serial No. 109,037

Term of patent 14 years

To all whom it may concern:

Be it known that I, John B. Buller, a citizen of the United States, residing at St. Joseph, in the county of Buchanan, State of Missouri, have invented a new, original, and ornamental Design for a Handle for a Safety Razor, of which the following is a specification, reference being had to the accompanying drawing, forming part thereof.

I claim:

The ornamental design for a handle for a safety razor, as shown.

JOHN B. BULLER.
